UNITED STATES PATENT OFFICE.

GEORGE W. SWIFT, JR., OF BORDENTOWN, NEW JERSEY.

PROCESS FOR MAKING WINDOW-ENVELOPS.

1,276,282.

Specification of Letters Patent. Patented Aug. 20, 1918.

Application filed November 27, 1917. Serial No. 204,184.

To all whom it may concern:

Be it known that I, GEORGE W. SWIFT, JR., of Bordentown, in the county of Burlington and State of New Jersey, have invented 5 a certain new and useful Process for Making Window-Envelops, whereof the following is a specification, reference being had to the accompanying drawings.

In this art it has heretofore been the practice in the use of processes for continuously manufacturing window envelopes from a progressing web to punch or cut perforations therein at suitable intervals. Simultaneously a transparent patch web is advanced 10 and patches cut therefrom and properly applied to each of said perforations, in order to form a succession of windows each covered by a transparent patch. Thereafter the web is cut to form individual envelop 15 blanks each containing a patched window in proper position to permit the formation therefrom of the desired window envelopes.

In order that the patches cut from the patch web may properly register with the 20 perforations cut in the envelop web, care must be taken to accurately synchronize the motion of the two webs. I have found that difficulty arises when it is thus attempted to continuously and evenly advance the envelop 25 web perforated at intervals because of the large apertures required to make the windows. This is due to the unsteadiness of an envelop web thus perforated. Such web is necessarily advanced under some tension, 30 and when perforated by large transverse apertures at intervals, as has been practised in this art, it tends to stretch. This tendency to stretch produces an unsteady motion which prevents the accurate application of 35 each patch to each window.

In order to overcome this difficulty according to my present invention, I have devised a scheme of operation by means of 40 which the patch material is applied to parts of a moving envelop web which have no window openings, but in such relation to the web that when the web is subsequently perforated and folded and cut to form individual envelopes, each envelop will contain 45 a patch properly applied to and protecting its window. Accordingly, my process is characterized by the following steps, namely: the continuous progression of envelop material; the attachment to parts thereof while still intact of transparent 50 patch material; the subsequent formation

of window openings at proper intervals in said material; and the folding and cutting of the material for the formation of envelopes, in the course of which the patch material required for each envelop is by such process of folding brought into proper relation to the window aperture to enable it to be secured in proper relation thereto.

This process of operation by which the patch material is applied to the envelop material before the window openings are formed, and whereby the formation of the envelop itself accomplishes the proper juxtaposition of the window patch to its window opening, is capable of being carried out by a variety of mechanisms. I will briefly describe a suitable mechanism for carrying it out.

In the accompanying drawings, Figure I, 55 is a diagrammatic view of the advancing envelop web with patches of window material successively applied thereto.

Fig. II, is a view of the envelop blank 60 cut therefrom.

Fig. III, is a cross sectional view showing the transfer position of the patch when the envelop is folded, whereby the said patch is brought into proper juxtaposition to be secured to the window envelop.

Fig. IV, is a simplified form of mechanism for accomplishing the progress of the envelop web, showing the succession of groups of devices, whereby the successive steps of my process may be practised.

Figs. V, VI, VII, and VIII, are detailed views of certain of these devices, as will hereafter be described.

Referring to Fig. IV, 1, is the roll of envelop material. As it unrolls, this material 75 passes from the feed rolls 2, 2, to the trimming rolls 3, 3, where the edges of the envelop web are trimmed for the formation of the side flaps. These mechanisms are well-known in the art.

The envelop web, which is still continuous and unperforated, next passes over a curved table 5, above which rotates a pressure roll 6. These are the instrumentalities employed to apply patches of transparent 105 window material to the unperforated envelop web at proper intervals. Upon reference to Fig. IV, it will be understood that the patch web roll 10, supplies the material for these patches. As it is advanced, it 110 passes between the rolls 11, 11, where it receives at intervals upon its lower surface an

application of gum 12, gumming the lower edge of each patch which is to be subsequently cut from the patch web. Thus gummed the patch web passes between the feed rollers 13, 13, and the cutting rollers 14, 14; whereby it is severed into individual patches, (each having the extreme lower edge gummed) upon what has now become its upper surface opposite to the lower surface of the envelop web beneath which it is fed. From these cutting rolls each patch slides over the curved table 5, whereby it is led into contact with the lower surface of the envelop web. At the same time the roller 6, effects a depression of the envelop web by reason of pad 7, which presses said web against the gummed lower edge of the patch, producing adhesion of the patch to it.

29 The advancing envelop web carrying these patches adhering to proper parts of it next passes between the cutting rolls 20, 20, (Fig. VI), whereby other parts of it are perforated with the formation of successive windows therein. These windows 21, are not in the immediate region of the previously applied patches, but in such relation thereto that, as a result of the subsequent steps by which is accomplished the formation of the envelop, the folding of the material will ultimately bring the patch in the desired relation to the window.

Thus the successive positions of the patches on the envelop web are determined and fixed while it is an unperforated web, by reason of which fact the relation of the patches to the web is more accurately determined than by processes heretofore in use in this art, in which the patches are not applied to the web until after it is perforated.

After the window opening has been cut, the envelop web continues to advance and as it passes between the rolls 25, 25, (Fig. VII) adhesive is applied to the lower side of each window patch in the form of gum strips, of which 26, 26, correspond to the long edges of the window patch and 27, 27, to the short edges. Further advancing, the envelop material passes between rolls 30, 30, (see Fig. VIII), where the envelop material is folded and cut and the process of envelop formation begins. These rolls and the accompanying mechanism are shown in section in Fig. VIII, and are substantially identical with similar envelop forming mechanism shown and described by me in Letters Patent of the United States No. 866,978, granted to me under date of September 24, 1907. It is, therefore, unnecessary for me to again describe the operation of this mechanism, further than to point out that the fold or crease 40, where the lower edge of the envelop is formed, takes place at a point which results in folding each patch

in the region of its lower gummed edge along the line 41, (see Fig. III). Following this fold the back of the envelop comes into its normal position in relation to the front of the envelop, so that the patch is now for the first time brought into its ultimate relationship to the window of the envelop, the gummed strips 26, 26, 27, 27, immediately occasioning the proper adhesion of the patch to the window opening 75 which it is to protect. Thereafter, the process of envelop formation and completion proceeds as heretofore practised in the art.

If reference be had to Fig. III, which is a longitudinal central section through the completed envelop blank, it will be noted that the patch 15, is adherent to the inside of the envelop at 16, where its lower edge was originally gummed to it; at 17, which is the lower edge of the window patch 85 where it carries one of the gummed strips 26; and at 18, which is the upper edge thereof, where it carries the other gummed strip 26.

From the foregoing description it will be understood that it is characteristic of my process that the envelop web is not perforated for the formation of window openings until after the window material has been applied to certain proper parts of it, and that thereafter the window openings are punched therein and the individual envelop blanks severed therefrom and folded: and that it is in the operation of envelop formation and not before, that each patch 100 is for the first time brought into proper relation to the window opening to which it is to be permanently secured and which it is to protect. After the patch has adhered to the envelop by reason of the gummed strips 26, 105 26, 27, 27, there is no longer any necessity of continuing adhesion along the gummed line 12, and I therefore employ a temporary adhesive gum at this point.

Having thus described my invention, I 110 claim:

1. The process of making window envelops which consists in continuously advancing unperforated envelop material; applying window material to parts only of the envelop material; perforating other parts of the envelop material at intervals for the formation of window openings; and folding and cutting the material for envelop formation, whereby the folding operation brings 120 a patch of window material into proper relation to each window opening.

2. The process of making window envelops which consists in continuously advancing unperforated envelop material; 125 applying window material to parts only of the envelop material by a temporary adhesive; perforating other parts of the envelop material at intervals for the formation of window openings; and folding and cutting 130

the material for envelop formation, whereby the folding operation brings a patch of window material into proper relation to each window opening, where it is secured by a permanent adhesive.

3. The process of making window envelopes, which consists in progressing an endless web of unperforated envelop material; applying to such unperforated envelop material at properly spaced intervals transparent window patches; then perforating the envelop material at proper intervals for the

formation of window openings; and folding and cutting the material, whereby each patch is brought into proper relation to the window opening of the envelop.

In testimony whereof I have hereunto signed my name at Bordentown, N. J., this twenty-fourth day of November, 1917.
